US00D920335S

(12) **United States Design Patent** (10) Patent No.: **US D920,335 S**
(45) Date of Patent: **** May 25, 2021**

(54) **CASE FOR PORTABLE DISPLAY DEVICE**(71) Applicant: **Apple Inc.**, Cupertino, CA (US)

(72) Inventors: **Jody Akana**, San Francisco, CA (US); **Bartley K. Andre**, Palo Alto, CA (US); **Jeremy Bataillou**, San Francisco, CA (US); **Daniel J. Coster**, San Francisco, CA (US); **Daniele De Iuliis**, San Francisco, CA (US); **M. Evans Hankey**, San Francisco, CA (US); **Julian Hoenig**, San Francisco, CA (US); **Richard P. Howarth**, San Francisco, CA (US); **Jonathan P. Ive**, San Francisco, CA (US); **Duncan Robert Kerr**, San Francisco, CA (US); **Shin Nishibori**, Kailua, HI (US); **Matthew Dean Rohrbach**, San Francisco, CA (US); **Peter Russell-Clarke**, San Francisco, CA (US); **Christopher J. Stringer**, Woodside, CA (US); **Eugene Antony Whang**, San Francisco, CA (US); **Rico Zörkendorfer**, San Francisco, CA (US)

(73) Assignee: **Apple Inc.**, Cupertino, CA (US)(***) Term: **15 Years**(21) Appl. No.: **29/679,892**(22) Filed: **Feb. 11, 2019****Related U.S. Application Data**

(63) Continuation of application No. 29/586,557, filed on Dec. 5, 2016, now Pat. No. Des. 840,405, which is a continuation of application No. 29/500,365, filed on Aug. 25, 2014, now Pat. No. Des. 773,454, which is a continuation of application No. 29/415,927, filed on Mar. 15, 2012, now Pat. No. Des. 713,402, which is a continuation-in-part of application No. 29/415,035, filed on Mar. 6, 2012, now abandoned, and a continuation of application No. 29/415,062, filed on

Mar. 7, 2012, now Pat. No. Des. 688,251, which is a continuation of application No. 29/415,035.

CLAIM

The ornamental design for a case for portable display device, as shown and described.

DESCRIPTION

FIG. 1 is a top front perspective view of a case for portable display device in an open position showing the claimed design;

FIG. 2 is a bottom rear perspective view thereof;

FIG. 3 is a front view thereof;
FIG. 4 is a rear view thereof;
FIG. 5 is a bottom view thereof;
FIG. 6 is a top view thereof;
FIG. 7 is an enlarged left side view thereof;
FIG. 8 is an enlarged right side view thereof;
FIG. 9 is a front view thereof showing the case for portable display device in a closed position;
FIG. 10 is an enlarged bottom view in two parts; and,
FIG. 11 is an enlarged top view in two parts.

The dashed broken lines in the figures show portions of the case for portable display device that form no part of the claimed design.

The dot-dash broken lines in the figures show boundaries that form no part of the claimed design.

The shade lines in the figures show contour or transparency and not surface ornamentation.
